FUSE FOR AN EXPLOSIVE PROJECTILE

Johannes Hermann Schuler, Uterluss, Kreis Celle, and Ulrich Theile, Steinhorst Über Celle, Germany, assignors to Aktiebolaget Bofors, Bofors, Sweden, a Swedish corporation

Application October 20, 1954, Serial No. 463,577

11 Claims. (Cl. 102—70.2)

The present invention relates to fuses for explosive projectiles and other missiles, and more particularly to self-arming and self-igniting fuses.

One of the objects of the present invention is to provide a novel and improved fuse of the general class above referred to, the operating mechanism of which is entirely inert when and as long as a projectile equipped with the fuse is at rest (as distinguished from a projectile in flight) and is automatically activated when the projectile is in flight.

Another object of the invention is to provide a novel and improved fuse having an operating mechanism actuated by a potential source of energy which produces the energy required for activating the fuse mechanism only in response to a physical magnitude acting upon a projectile in flight but is entirely inert until the projectile is fired thereby effectively preventing a detonation of the projectile by accidental impact against its fuse or similar causes.

Still another object of the invention is to provide a novel and improved fuse with an operating mechanism including a circuit system which by the action of said physical magnitude for a predetermined period of time is energized sufficiently to initiate the ignition of the fuse in response to an impact caused for instance by the projectile hitting a target and which after a further predetermined period of time is energized sufficient to initiate the ignition of the fuse without the agency of an impact. Such an arrangement affords the advantage that the fuse is automatically changed from its initial inert condition to an armed condition for detonation of the fuse by impact and is destroyed by self-detonation a predetermined period of time after the period of time required by the projectile to reach the target at which it is aimed.

A further object of the invention is to provide a novel and improved fuse, the operating mechanism of which automatically reverts to its inert condition if due to any defect the mechanism fails to initiate the detonation of the fuse after both the period of time for detonation by impact and the period of time for self detonation have passed, or in other words if the projectile is a dud. This affords the advantage that the fuse of such a dud after it falls back on the ground, usually in friendly territory, can be dismantled without danger to service personnel.

A still further object of the invention is to provide a novel and improved fuse, the source of energy of which for actuating the fuse mechanism does not contain any components subject to deterioration during storage or requiring servicing from time to time so that projectiles equipped with fuses according to the invention can be safely stored for an infinite period of time.

Other and further objects, features and advantages of the invention will be pointed out hereinafter and set forth in the appended claims forming part of the application.

2

In the accompanying drawing a preferred embodiment of the invention is shown by way of illustration and not by way of limitation.

In the drawing:

Fig. 1 is a sectional longitudinal view of a projectile equipped with a fuse according to the invention, and

Fig. 2 is a circuit diagram of the operating mechanism of the fuse.

Referring now to the figures in detail, the projectile according to Fig. 1 comprises a shell case 1, to the forward end of which the fuse according to the invention is screwed, separated from the shell casing by a flanged screw washer 4. The operating mechanism of the fuse is disposed within a metal fuse casing composed of a rear part 2 and a nose part 3. In this connection it may be mentioned that a fuse according to the invention may also be mounted in or on a part of the projectile other than the nose end thereof, such as the rear part of the shell.

20 The shell case 1 is filled with bursting or explosive charges 5 and 6. The relation and coaction of these two charges are not essential for the understanding of the invention.

25 The operating mechanism of the fuse which is disposed in casing 2, 3, comprises two preferably cylindrical capacitors 7 and 8, separated by a partition wall formed within the fuse casing by casing part 2, a resistor 9 preferably fitted in an annular groove of said partition wall and a circuit control means in form of a discharge tube 10 fitted in the space circumscribed by capacitor 7. The outer wall of capacitor 7 together with the respective wall portions of casing part 2 form an annular chamber 11 from which extend one or several rearwardly slanted ducts or channels 12 leading to the outside wall of fuse 30 part 2. Each of these channels is lined with a metal tube 13, electrically insulated from casing part 2. The outer end of each channel 12 is plugged by means of a plug 14 made of lead or other comparative soft material. The closed spaces formed by channels 12 and chamber 11 are 35 filled with a non-conductive powdered material such as glass or colophony. The fuse mechanism further comprises an electrical detonating or igniting device 16 and a detonation initiator 17, both of conventional design and disposed below capacitor 7 and encased by a generally cup-shaped member 20. The mechanism finally comprises a switch 18 disposed in an axial bore of nose part 3 of the fuse casing. This switch is normally open and can be closed by an impact experienced by the projectile or more specifically by the fuse thereof. The switch is 40 diagrammatically shown as comprising an upper contact 19 and a lower contact 19, the latter being insulated from nose part 3 by an insulation disc 21.

The circuit connections of the aforescribed components of the fuse mechanism are shown in Fig. 2. According to this figure, one of the electrodes of capacitor 7 is connected to metal tubes 13 and the other is grounded, that is, it is connected to the fuse casing or to the part 2 thereof only, in which event casing part 3 may be made of non-conductive material. Capacitor 8 and resistor 9 are connected in series across the terminals of capacitor 7, and discharge tube 10 and igniter 16 are connected in series across the terminals of capacitor 8. Finally, switch 18 is connected across the terminals of tube 10. All the components of the circuit system are, of course, suitably insulated one from the other but the insulation materials used for this purpose have preferably a finite value for a purpose which will be more fully explained hereinafter.

The operation of the fuse as hereinbefore described, is as follows:

As is apparent, there is no energy available which

could cause activation of detonator 16 even though switch contacts 18 were closed for instance by an accidental impact when and as long as the projectile is at rest, or in other words, the fuse according to the invention is completely safe prior to firing of the projectile mounting the fuse.

Let it now be assumed that the projectile is fired, say from a rifled barrel. The centrifugal force acting upon the spinning projectile in flight will cause expulsion of plugs 14. As a result, the powdered material 15 in chamber 11 and ducts 12 will be ejected. After leaving the ducts, the powdered particles will come in contact with the respective wall portions of casing part 2 connected to one electrode of capacitor 7. The friction between the powdered particles and tubes 13 which are connected with the other electrode of capacitor 7 will generate an electrostatic charge and carry the electrons of this charge from one electrode of capacitor 7 to the other electrode thereof. Consequently, capacitor 7 will be gradually charged during the ejection of the powdered particles. As the charge of capacitor 7 increases, it will begin to charge capacitor 8. The rate of charge at which capacitor 8 is charged obviously depends upon the capacitances of capacitors 7 and 8 and the ohmic resistance of resistor 9.

The charge of capacitor 8 increases until this charge has reached a predetermined maximum value corresponding to the potential required for tube 10 to become conductive. As soon as the tube becomes conductive, capacitor 8 discharges through detonator 16. As a result, detonator 16 initiates through the initiator 17 the detonation of the explosive charges 5 and 6 of the projectile.

The aforescribed detonation of the projectile by the agency of tube 10 constitutes the aforementioned self-destroying feature of the fuse.

Let it now be assumed that the projectile strikes a target prior to capacitor 8 reaching the break-down potential of tube 10 but after having been charged to a predetermined intermediate value. Then the impact of the target against the fuse will close switch contacts 18 thereby short circuiting tube 10. The intermediate charge of capacitor 8 is now sufficient to cause the capacitor to discharge through detonator 16 whereby the detonation of the projectile is initiated.

As appears from the previous description, the fuse is armed for operation by impact only for the period of time required by capacitor 8 to increase its predetermined intermediate charge to its predetermined maximum charge at which it can discharge through tube 10. The initial period of time between the firing of the projectile and 50 until capacitor 8 reaches its predetermined intermediate charge constitutes a safety factor. This safety factor can be conveniently controlled by suitably correlating the capacitors and the resistor; it may be such that the projectile must travel a distance between 70 and 200 ft. or 55 more from the muzzle of the barrel before its fuse becomes armed.

Finally, let it be assumed that for any reason such as a defect, the projectile is not automatically destroyed when capacitor 8 has reached its maximum final charge. As previously mentioned, the insulation materials used for insulating the respective components of the fuse are of finite values. These values are so selected that the charges of capacitors 7 and 8 are substantially dissipated during the time the projectile is in flight. Consequently, 60 the fuse is reverted to its initial energy-less or inoperative condition at about the time it falls back on the ground. This feature permits service personnel to collect duds and to disassemble the same without danger and also protects the civilian population.

As appears from the previous description, particularly from the discussion of Fig. 2, the circuit means including capacitor 8 and resistor 9 function as an ignition circuit in which capacitor 8 constitutes the ignition capacitor. The capacitor 7 together with the fuse casing and tubes 75

13 connected thereto function as an energizing circuit in which capacitor 7 constitutes the source of power. Accordingly, capacitor 7 is sometimes referred to as power capacitor. It is further evident that the concept of the invention is not limited to using a capacitor as source of power or as storage for energy although the use of a capacitor is the preferred form of the invention. An alternative power supply may be formed by an electrostatic generator which is driven by a physical magnitude 10 acting upon the projectile when in flight, such as the centrifugal force developed by the spinning of the projectile. Another means of generating the necessary energy during the flight of the projectile is a dynamo rotated by the forces resulting from the spinning of the projectile.

While the invention has been described in detail with respect to a certain now preferred example and embodiment of the invention it will be understood by those skilled in the art after understanding the invention, that various changes and modifications may be made without departing from the spirit and scope of the invention, and it is intended, therefore, to cover all such changes and modifications in the appended claims.

What is claimed as new and desired to be secured by Letters Patent is:

1. A self-arming and self-igniting fuse for an explosive missile, comprising fuse ignition means, circuit means co-acting with said ignition means for igniting the same in response to an energization of said circuit means, energizing means connected with said circuit means for supplying energy to the same, said energizing means including power capacitance means and a metal fuse casing including a chamber, powdered insulation material in said chamber, said casing having at least one duct leading from said chamber to the outside of the casing at a slant rearwardly relative to the direction of flight of the missile, a metal lining for said duct electrically insulated from said casing, one electrode of said power capacitance means being connected to said lining and the other to said casing whereby the powdered material is ejected from said chamber when said missile is in flight and the friction between said material and said lining and the contact of ejected material with said casing effect charging of said power capacitance means, the energizing means being gradually charged from an initial substantially zero minimum charge to a maximum charge by said ejection of the powdered material, said maximum charge energizing said circuit means for igniting the ignition means, and normally open switch means connected in a circuit including said circuit means and said energizing means, said switch means being closed by an impact experienced by the fuse, closing of said switch means effecting energization of said circuit means for the purpose aforesaid only when the charging of said energizing means is above a predetermined intermediate value.

2. A fuse according to claim 1, wherein the said circuit means include circuit control means activating said circuit means for igniting said ignition means in response to said maximum charge, said switch means being connected in shunt to said control means for short circuiting the same by closing of the switch means whereby the charge required to energize said circuit means is reduced to said intermediate value.

3. A fuse according to claim 2, wherein the said circuit control means comprise discharge tube means, said tube means becoming conductive in response to said maximum charge.

4. A fuse according to claim 1, wherein the said circuit means include ignition capacitance means, circuit control means and said ignition means, said control means being responsive to said maximum charge to effect discharge of said ignition capacitance means for the purpose aforesaid, and wherein the said energizing means are connected in a charging circuit including said power capacitance means with said ignition capacitance means.

5. A fuse according to claim 4, wherein the said circuit means further include time-delay means delaying charging of said ignition capacitance means by said energizing means for a predetermined period of time.

6. A fuse according to claim 5, wherein the said time delay means comprise resistance means.

7. A fuse according to claim 6, wherein the said ignition capacitance means and said resistance means are connected in series across the terminals of said power capacitance means, and wherein the said ignition means and the said circuit control means are connected in series across the terminals of the ignition capacitance means, and wherein the said switch means are connected across the terminals of the circuit control means.

8. A fuse according to claim 7, wherein the resistances of the insulation materials insulating the components of said circuit means and said energizing means one from another have values such that upon a failure of the fuse to be ignited in response to a maximum charge of said energizing means, the charges of both the capacitance means are gradually dissipated whereby the fuse is rendered inoperative for ignition by impact.

9. A self-arming and self-igniting fuse for an explosive missile spinning when in flight, said fuse comprising electrically operable fuse ignition means, circuit means connected to said ignition means for operating the same upon energization of said circuit means, means for energizing said circuit means, said energizing means comprising a metal fuse casing including a chamber, powdered insulation material in said chamber, said casing having at least one duct leading from said chamber to the outside of the casing at a slant rearwardly relative to the direction of flight of the missile, a metal lining in said duct elec-

trically insulated from said casing, and capacitance means having one electrode connected to said lining and the other to said casing whereby the powdered material is ejected from said chamber when the missile is in flight and the friction between the said material and said metal lining and the contact of the ejected material with the casing effect charging of said capacitance means, the charge of the capacitance means being fed to said circuit means to energize the same for igniting said ignition means in response to a capacitor charge above a pre-determined value.

5 10. A fuse according to claim 9 and further comprising impedance means included in said circuit means and normally open switch means closable by impact and connected in shunt with said impedance means, closing of

15 said switch means short circuiting said impedance means to energize said circuit means for operating the ignition means in response to a capacitor charge of a pre-determined value below the aforesaid pre-determined value.

10 20. A fuse according to claim 9, wherein a plug is inserted in the outer end of said duct for sealing the same, the said plug being fitted for ejection by the effect of the centrifugal force acting upon the fuse when the missile is in flight.
